UNITED STATES PATENT OFFICE.

PAUL F. KAHLER, OF CHICAGO, ILLINOIS.

PHOTOGRAPHIC-PRINTING FRAME.

Application filed March 1, 1926. Serial No. 91,545.

This invention relates to photographic printing frames and has for its principal object the provision of an improved construction of this character which will be 5 highly efficient in use and economical in manufacture.

A further object of the invention is the production of a device of this character wherein there is provided a simple combination and arrangement of parts for effectively holding sensitized printing sheets in proper contact with the negative plate or film.

A further object of the invention is the provision for facilitating the positioning of 15 a sensitized printing sheet under a negative plate or film for proper exposure.

Other objects will appear from the detailed description hereinafter set forth.

The invention consists in the combination 20 and arrangement of parts hereinafter described and claimed.

The invention will be best understood by reference to the accompanying drawing, illustrating the preferred form of construction, and in which;

Fig. 1 is a front elevational view of the invention.

Fig. 2 is a rear view of the invention.

Fig. 3 is a sectional detailed view of the 25 same, taken substantially on line 3-3 of Fig. 1.

Fig. 4 is a sectional detailed view of the same taken substantially from line 4-4 of Fig. 3.

35 It is well known to those skilled in the art that, in a device of the character herein mentioned and hereinafter described, if the sensitized printing sheet is not positioned so that its entire adjacent surfaces contact 40 with the negative plate or film, that the finished photograph or print will be uneven in shade and possess unsightly high spots rendering the photograph or print defective.

It is therefore one of the many objects 45 of the invention to provide a simple combination and arrangement of parts for assuring uniform contact between the surfaces of the printing sheet and the adjacent surfaces of the negative plate or film.

50 To accomplish this and other objects of the invention, I provide a frame 10 defining a back 11 and side walls 12 having inturned edge portions 13 defining together with the side walls 12 and the back 11 opposite channels 14. A tongue 15 is struck inwardly from body of the back 11 to provide a stop

or rest 16 as well as a guide, for reasons hereinafter set forth. This tongue passes through a slot 17 formed in a pressure plate 18 of metallic material. This pressure plate 60 is normally pressed into contact with a separating sheet 19 formed of such material as will best serve the purpose and forwardly of which is arranged a sensitized printing sheet 20 and a glass negative plate 20. The separating sheet, sensitized printing sheet and negative plate are supported when mounted with their edge portions 21 disposed in the channels by the tongue 15. This tongue serves in its principal capacity as a guiding 70 member for guiding the pressure plate 18 into uniform contact with the separating sheet which in turn is forced by the pressure plate into uniform contact with the sensitized printing sheet for pressing this sensitized printing sheet into uniform contact with the negative plate 20 for proper exposure beneath the negative plate.

The pressure plate is urged into pressing position by the resilient fingers 22 disposed in staggered relation and struck inwardly from the body of the back 11.

In assembling the separating sheet, sensitized printing sheet and negative plate, it is apparent that the tongue 15 serves to facilitate proper positioning of these members and also that the tongue 15 serves to guide the pressure plate when urged into contact with the separating sheet.

As illustrated in Fig. 3 of the drawing 90 the separating sheet 19 is scored transversely as at 2' intermediate its top and lower edge portions permitting the portion 3' of this sheet to be folded rearwardly together with a portion of the sensitized printing sheet 95 away from the negative plate when the separating sheet, sensitized printing sheet and negative plate are partially withdrawn from confined position in the frame with the score line 2' of the separating sheet disposed exterior of the frame. This permits one to observe the sensitized printing sheet without completely withdrawing the printing sheet from confined position in the frame.

100 From the description herein it is manifest that I provide a simple combination and arrangement of parts for effectively urging pressing action of the pressure plate and that such combination and arrangement of parts greatly facilitate the assembly of the 105 separating sheet, sensitized printing sheet and negative plate.

110

When a negative film is substituted for the negative plate 20 a sheet of glass is substituted for the negative plate and this film is disposed between the sensitized printing sheet and glass at a point indicated at 22', Fig. 4.

While I have shown and described the preferred form of my invention, it is to be understood that various changes and alterations may be carried out in manufacture without departing from the spirit of the invention or the scope of the appended claims.

The device having been set forth, what I claim as new and useful is:

1. A photographic printing frame provided with channel side walls, resilient fingers struck from the body of the back of said frame in staggered relation, substantially as

shown; said channel side walls having inwardly turned edges for the accommodation therebetween, of a pressure plate, separating sheet, glass plate, and the photographic print and negative.

2. A photographic printing frame comprising inwardly bent sides forming channel trackways for the accommodation, therebetween, of pressure plate, separating sheet, photographic print and negative, and glass plate, resilient pressure elements struck from the back portion of said frame, in staggered relation, substantially as shown, and a tongue or stop struck from and depending inwardly of the back portion of said frame.

In testimony whereof I affix my signature.

PAUL F. KAHLER.
